INVENTOR: GEORGE L. BROWNELL.
BY Rufus B. Fowler
ATTORNEY.

UNITED STATES PATENT OFFICE.

GEORGE L. BROWNELL, OF WORCESTER, MASSACHUSETTS.

TWISTING MECHANISM.

SPECIFICATION forming part of Letters Patent No. 689,786, dated December 24, 1901.

Application filed January 24, 1898. Serial No. 667,693. (No model.)

To all whom it may concern:

Be it known that I, GEORGE L. BROWNELL, a citizen of the United States, and a resident of Worcester, in the county of Worcester and State of Massachusetts, have invented a new and useful Improvement in Twisting Mechanism, of which the following is a specification, accompanied by drawings forming a part of the same, in which—

10 Figure 1 represents a side elevation of a twisting mechanism embodying my invention. Fig. 2 is a sectional view of a portion of the same shown on line 2 2, Fig. 1; and Fig. 3 is a sectional view of that portion of 15 the mechanism shown in Fig. 2 with the section taken on line 3 3, Fig. 2.

Similar letters refer to similar parts in the different figures.

My invention relates to a mechanism for 20 twisting twine or cord; and it has for its objects to provide an improved traversing mechanism by which the twine or cord is laid evenly upon the winding-spool, and also to provide means whereby the individual strands 25 are moved along upon the edge of a water-cup; and it consists in the construction and arrangement of parts as hereinafter described, and set forth in the annexed claim.

Referring to the drawings, A denotes a portion 30 of the framework of a twisting-machine, which is shown in sectional view in order to disclose the operative parts of the machine, which are of a well-known form of construction, comprising a rotating flier-frame B, consisting of a disk C, upright flier-arms D D', connected at the top by a cross-bar D² and carried by a revolving spindle D³.

E denotes the winding-spool upon which the 35 twisted cord is wound and held concentrically 40 within the flier-arm.

Attached to the framework of the machine is an upright bar F, forming a way for a vertically-sliding rack G, provided with teeth G', which are engaged by a pinion H, attached 45 to a shaft H', which is rotated a single revolution in opposite directions by means of a mangle-wheel H² and the usual connecting mechanism, causing a reciprocating motion 50 to be given to the sliding rack G on the bar F. The rack G is provided with a bracket I, to which is attached a ring J, held concentrically with the rotating flier-frame B. The

ring J is provided at its lower edge with an interior flange J' and at its upper edge with a removable flange J², the two flanges J' and J² inclosing a groove J³ upon the inner side of the ring. The upright flier-arms D and D' carry sleeves K K', preferably formed of aluminium in order to reduce their weight to a minimum and lined or bushed with sheets K² of vulcanized fiber to reduce the friction upon the flier-arms. Upon the side of the sleeves K K' next the ring J is a screw-threaded stud K³, preferably integral with the sleeve, upon which is screwed a rectangular block of vulcanized fiber K⁴, adapted to slide in the groove J³ of the ring J, and upon one of the adjacent sides of the sleeves are lugs K⁵, having eyes K⁶, through one of which the twisted cord L, Fig. 1, is conducted 65 to the winding-spool. As the flier-arms D D' are rotated the sleeves K K' are carried around the winding-spool, and the cord, passing through the eye K⁶ of one of the sleeves K K', becomes wound thereon and is evenly 70 traversed or laid upon the winding-spool by the rising-and-falling motion of the ring J, which slides the sleeves K K' up and down upon the flier-arms D D'. The sleeves K K' are duplicates and are carried upon each of 75 the flier-arms D D' in order to balance the flier-frame, and the lugs K⁵ are traversed the distance between the heads of the winding-spool by the rising-and-falling motion of the ring J, actuated by the mangle-wheel H² and 80 connected operating mechanism.

In the traversing mechanism above described the rotating parts driven by the flier-arms D D' consist only of the light aluminium sleeves with their bushing of vulcanized fiber, so that but little momentum is added 90 to the flier-arms, and the contact between the stationary ring and revolving parts of the mechanism is limited to the contact of the flanges J' J² with the upper and lower 95 sides of the small rectangular block K⁴ of vulcanized fiber, thereby decreasing the friction between the moving and stationary parts.

The flier-arms D and D' are preferably rectangular in cross-section and are grooved 100 on opposite sides, as at D⁴, in order to reduce the weight of the arms. The sleeves K K' are preferably longer than the width of the ring J to provide a bearing upon the flier-

arms long enough to prevent the binding of the sleeves on the arms as the sleeves are moved up and down upon the arms by the rising-and-falling motion of the ring J, and 5 the block K⁴ is also preferably rectangular to furnish a bearing-surface against the flanges J' and J² and prevent the block from unscrewing upon the screw-threaded studs K³. The upper flange J' of the ring J is removable in order to permit the blocks K⁴ to become released from the groove J³ and allow the blocks K⁴ to be replaced when worn.

I am aware that a traverse mechanism comprising a rotating ring carrying cord-guides and driven by the flier-arms in a guideway having a rising-and-falling motion is not new, and I do not herein claim such. 15

My improved traverse mechanism enables me to attain a very high speed of the flier-arms with a slight friction of the moving parts and with a very slight increase in momentum. By increasing the length of the sleeves upon the flier-arms I counteract the drag or twisting effect of the cord or twine 20 upon the guides and transfer any increase in pressure from the ring J and blocks K⁴ to the sleeves and the flier-arms or from rapidly-moving surfaces to slowly-moving surfaces, and thereby prevent an undue increase in 25 friction.

In machines of this class it is frequently necessary to revolve the flier-frame at a very high speed, and it is desirable to reduce both the friction and the momentum of the moving parts, and I therefore carry the cord-guides upon sleeves which are carried by the flier-arms which are parallel with their axes 35 of rotation and serve as guideways for the sleeves, thereby securing a long bearing upon 40 the flier-arms to resist the twisting strain of the cord upon the guides and reduce the weight of the moving parts to a minimum

and also decrease the bearing-surfaces which are in rapid motion.

The twisted cord L is composed of individual strands taken from the spools 1, 2, and 45 3, two of these strands being shown at a a'.

The individual strands are carried over the upper edge of a cup M, filled with water, and each strand is depressed beneath the surface 50 of the water held in the cup M by being carried beneath the foot N, in order to wet the strands as they pass to the twisting and winding mechanism. Each of the strand-spools 1, 2, and 3 is supported upon a rotating table O, provided with a hub O', to which is attached a worm-gear P, engaged by an actuating-worm P' on a rotating shaft P² in order to cause the strands as they are conducted from the strand-spools 1, 2, and 3 55 to be moved along the edge of the stationary water-cup M and prevent grooves from being worn in the edge of the cup.

What I claim as my invention, and desire to secure by Letters Patent, is— 65

In a twisting mechanism, the combination of a flier-arm parallel with its axis of rotation and polygonal in cross-section, means for rotating said flier-arm, a sleeve capable of longitudinal movement thereon and fitting 70 said flier-arm, whereby it is held from rotation relatively to said arm, a cord-guide projecting from one side of said sleeve, a block 75 attached to the outer side of said sleeve, a ring provided with a groove receiving said block and means for imparting a traversing movement to said ring parallel with the axis of rotation of said flier-arm, substantially as described.

Dated this 17th day of January, 1898.

GEORGE L. BROWNELL.
